UNITED STATES PATENT OFFICE.

SENA MAE WARD AND EUNICE S. SUTTON, OF NEW YORK, N. Y.

GARMENT HANGER.

Application filed September 15, 1922. Serial No. 588,319.

To all whom it may concern:

Be it known that we, SENA MAE WARD and EUNICE S. SUTTON, citizens of the United States, and residents, respectively, of 5 New York city, in the counties of Bronx and New York and State of New York, have invented certain new and useful Improvements in Garment Hangers, of which the following is a specification.

10 This invention relates to garment hangers, and more particularly to a ladies' dress hanger of the type shown in our Patent No. 1,420,890 of June 27, 1922; and has special reference to the provision of a hanger of 15 this type convertible for use with different kinds of ladies' garments.

A prime desideratum of our present invention comprehends the provision of a garment hanger for supporting ladies' full 20 dresses such as evening gowns with the attached waist and skirt portions of the dress or gown supported in an efficient manner, the hanger being constructed so as to be changeable or convertible for hanging other 25 ladies' garments such as detached skirts and waists and ladies' suits.

As disclosed in the aforementioned patent, the improved garment hanger has special applicability to the supporting of ladies' 30 dresses and more particularly those which comprise attached waist and skirt portions, the dresses being so supported or hung as to minimize or eliminate the distorting strains or stresses upon the waist due to the 35 weight of the skirt with the waist and skirt hung to assume their natural shape as intended for wear. In the use of these garment hangers the attached waist and skirt portions of a dress such as a lady's evening 40 gown are independently supported by spaced garment hanging members so that the distorting pulls of the relatively massive skirt portion, which is usually made of such relatively heavy material as serge or 45 jersey silk often further weighted as by being beaded or provided with spangles, is relieved from the relatively light waist portion of the dress which is usually made of a relatively frail material such as silk, satin 50 or chiffon; the said garment hanging members being spaced so that both the skirt and waist portions are supported or suspended to assume the natural folds as intended for wear by the user. By our present invention 55 we propose to provide a hanger of this type in which the attached skirt and waist por-

tions of a dress may be supported in a similar manner with the garment hanger constructed so as to be convertible or changeable for interchangeably hanging other garments, such as detached or independent skirts and waists or coats and skirts of ladies' suits, the hanger being thus adaptable to different needs or requirements of service.

The principal objects of our present invention may therefore be said to include, besides the provision of a garment hanger having the characteristics and capable of the uses above referred to; the further provision of a garment hanger in which is provided 60 an invertible garment supporting device provided with erect and inverted sides or ends adapted for hanging different kinds of garments when moved to erect or inverted positions; the further provision of a garment hanger in which are provided upper and lower garment hanging members for hanging or suspending the upper and lower portions of a garment, with the construction 65 such that the upper garment hanging member comprises an invertible device adapted for interchangeably hanging different upper garments; and the still further provision of a garment hanger of this nature which is constructed to be quickly and 70 easily adapted or converted as desired by the user.

To the accomplishment of the foregoing and such other objects as may hereinafter appear, our invention consists in the elements and their relation one to the other, as hereinafter particularly described and sought to be defined in the claims, reference being had to the accompanying drawing 75 which shows preferred embodiments of our invention, and in which:

Fig. 1 is a front elevational view of our garment hanger with parts shown in cross-section showing one manner of using the same.

Fig. 2 is a perspective view of our hanger showing another manner of using the same, and

Figs. 3 and 4 are front elevational views of a modification.

Referring now more in detail to the drawings and more particularly to Figs. 1 and 2 thereof, the garment hanger of the present invention comprises generally a garment supporting structure including the upper or shoulder member A and the lower or 80 waist member B suspendedly carried there-

by, the said members being intended for independently supporting attached waist and skirt portions 10 and 11 of an evening gown as shown in outline in Fig. 1 of the drawings. The shoulder and waist members A and B of the garment hanger are preferably spaced a distance corresponding to the distance between the shoulder and waist line of the human body, the construction and spacing being such that the skirt and waist portions 10 and 11 of the dress may be hung to assume and hold the form and shape as intended and desired for wear by the user.

15 As shown in Figs. 1 and 2, the upper or shoulder member A may comprise a preferably flat garment supporting member fashioned out of wood and provided with a substantially horizontal upper garment supporting face 12 for receiving the spaced straps or yoke members 13 of the waist and the opposite upturned portions 14 for effectively retaining the said strap or yoke members against outward movement and slipping from the shoulder member. The waist member B may comprise a wire or similar frame bent into the configuration shown in Figs. 1 and 2 and including the horizontal waist portion 15 provided with the spaced hooks or loops 16 intended for receiving skirt hanging elements such as the loop portions 17 sewed or otherwise attached to the skirt 11 and the integral side portions 18, the said side portions terminating in the inturned integral stud portions 19 received in sockets 20 in the opposite ends of the upper or shoulder member A.

As hereinbefore referred to, a desideratum of the present invention comprehends 40 the construction of a garment hanger which is adaptable or convertible for supporting or suspending other ladies' garments such as detached waists and skirts and ladies' suits, and to this end the upper garment hanging member A of our present invention comprises an invertible member movable from an erect position as shown in Fig. 1 of the drawings to an inverted position as shown in Fig. 2 of the drawings, 45 the garment hanger being intended for supporting one kind of garment in the erect position and for supporting other kinds of garments in the inverted position. In the inverted position the garment hanging member A is adapted for supporting for example the coat and skirt of a lady's suit, the inverted side of the upper garment hanging member A comprising to this end a supporting form for fitting a lady's coat or a full waist, the said inverted side being suitably contoured as shown at 21 for fittingly receiving the coat 22 of a lady's suit. The skirt of the suit may be suspended 50 from the hooks or loops 16 of the lower garment supporting member B as shown in

Fig. 2. By suspending the lower garment hanging member B from the upper hanging member A by means of the stud and socket connections 19 and 20, it will be seen that a pivotal or swivel connection is afforded and that the upper member A may be inverted for adapting the garment hanger to its different uses without changing the position of the lower garment hanging member, the lower or waist member B co-operating with the upper or shoulder member A in either of the erect or inverted positions of the latter.

For the purpose of supporting the garment hanger in either its erect or inverted positions, there is provided the supporting hook 23 which may comprise the parallel hook strands 23' and 23² rotatably mounted in the shoulder member A and connected by a transverse portion 24 threaded through an aperture 25 in the body of the said shoulder member, the construction being such that the hook 23 may be moved to the erect position shown in Figs. 1 and 2 of the drawings with the shoulder member A in either the erect or inverted positions. For the purpose of retaining the hook 23 in a stable erect condition in either of its positions, we may provide the hook retaining members 26 and 27 at the upper and lower sides of the garment hanging member A, the said hook retaining members each preferably comprising a grooved element for seating the strands 23' and 23² of the hook in the desired erect position.

In Figs. 3 and 4 we show a modification of the invention in which the lower garment supporting means B' comprises the flexible pendants 28 and 29 suspendedly carried by the upper or shoulder member A', the said pendants preferably comprising spacedly arranged cord or tape lengths threaded through apertures 30 and 31 in the shoulder member A', the doubled strands of the pendants terminating in the waist line or skirt securing elements 32 and 33. The securing elements 32 and 33 are also preferably spaced from the upper or shoulder member A' a distance substantially equal to the distance between the shoulder and waist line of the human body so that the attached skirt and waist portions 10' and 11' of a dress may receive independent support by the garment hanging members as hereinbefore referred to. The upper or shoulder member A', as in the form shown in Figs. 1 and 2, comprises an invertible garment supporting device having its erect and inverted sides provided with different garment supporting forms, the erect side including the substantially horizontal supporting face 12' and the spaced upturned yoke retaining portions 14' for suspending the evening waist 10' as shown in Fig. 3, and the inverted side including the shoul-

der form 21' for fitting the shoulder of a full waist or coat 22' of a lady's suit. As will be apparent from a consideration of the drawings, the pendants 28 and 29 are 5 reversible relatively to the shoulder member A', the attachment of the pendants to the shoulder member being such that the pendants will assume the suspended condition with the shoulder member arranged in 10 either its erect or inverted position. In the modification shown in Figs. 3 and 4, the supporting hook may comprise the oppositely curved hook portions 34 and 35 and a connecting straight portion 36, the hook 15 34 being intended for supporting the hanger in erect position and the hook 35 being intended for supporting the same in inverted position as clearly appears from a consideration of Figs. 3 and 4 of the 20 drawings.

The manner of making and using our improved garment hanger will in the main be apparent from the above detailed description thereof. It will be apparent that the 25 upper or shoulder member A or A' of the garment hanger may be inverted with facility and ease for adapting the same to the variety of needs met with in service, the said upper member cooperating with the lower 30 garment supporting means B or B' so that either attached or detached portions of a lady's dress or suit may be supported in an efficient manner.

While we have shown our device in the 35 preferred forms, it will be obvious that many changes and modifications may be made in the structure disclosed without departing from the spirit of the invention, defined in the following claims.

40 We claim:

1. A garment hanger comprising an upper member for supporting an upper garment and a lower member for supporting a lower garment suspended therefrom, the 45 upper member comprising a convertible garment supporting device provided with different garment hanging means at its erect and inverted sides for supporting different upper garments upon inversion of the same.

50 2. A garment hanger comprising an upper member for supporting an upper garment and a lower member for supporting a lower garment suspended therefrom, the upper member comprising a garment supporting body having erect and inverted sides differently contoured for selectively hanging different type garments upon inversion of the same.

55 3. A garment hanger comprising a structure providing an upper garment support-

ing member and a lower garment supporting member, the said members being spaced a distance corresponding to the distance between the shoulder and waist line of the human body, the upper member including 65 a convertible garment supporting device provided with different garment hanging means at its erect and inverted sides adapted upon inversion for hanging different upper garments whereby attached parts of a dress 70 may be independently supported by the said members with the upper member in erect position, and independent or detached parts of a dress may be supported by the said members with the said upper member in inverted position. 75

4. A garment hanger comprising a garment supporting member for supporting an upper garment such as a waist, and a plurality of spaced pendants suspended therefrom, 80 each of the said pendants being provided with means for attachment to a lower garment such as a skirt, the said upper member comprising a convertible garment supporting device provided with different garment hanging means at its erect and inverted sides. 85

5. A garment hanger comprising a garment supporting member for supporting an upper garment such as a waist, and a plurality 90 of spaced pendants suspended therefrom, each of the said pendants being provided with means for attachment to a lower garment such as a skirt, said means being spaced from the said member a distance 95 equivalent to the distance between the shoulder and waist line of the human body, the said upper member comprising a convertible garment supporting device provided with different garment hanging means at 100 its erect and inverted sides.

6. A garment hanger comprising an invertible garment supporting body having its erect and inverted sides differently contoured for selectively hanging different type upper garments upon inversion of the same, and a plurality of spaced flexible pendants suspended from the said body and adapted for supporting a lower garment, the said pendants being reversible relatively to the 105 said body whereby the pendants are adapted to support a lower garment with the garment supporting body in either its erect or inverted positions.

Signed at New York city in the county of New York and State of New York, this 12th day of September, A. D. 1922.

SENA MAE WARD,
EUNICE S. SUTTON.
